UNITED STATES PATENT OFFICE.

ALFRED MUNZER, OF NEW YORK, N. Y.

LAMP.

Application filed April 30, 1924. Serial No. 709,949.

To all whom it may concern:

Be it known that I, ALFRED MUNZER, a citizen of the United States, residing at New York, county and State of New York, have invented certain new and useful Improvements in Lamps, of which the following is a specification.

This invention relates to improvements in lamps, particularly those of an artistic or ornamental nature in the semblance of an old fashioned hoop-skirted lady in which the skirt forms a shade.

An object of the invention is to simplify and cheapen construction. Another object is to provide an article admitting of ready manufacture and assemblage. The skirt frame and bust of the figure are made separate, and the lamp socket is combined with the torso, and a secure and ready means of connecting the frame and bust are provided.

An embodiment of the invention is illustrated in the accompanying drawings, in which—

25 Figure 1 is a view of the lamp; the skirt-frame covering forming the shade being omitted.

Figure 2 is a view showing the connecting parts between the bust and skirt-frame, the latter part being shown detached.

Figure 3 is a detail view showing the socket for an electric filament lamp.

Referring to said drawings, numeral 10 designates a bust of a female figure, adapted to be dressed in clothes in the manner of a fancy doll representing an old fashioned lady. The bust may comprise a head 12, a torso 14, and arms 16, and in the torso 14 there is formed a socket 18, in which is placed the usual screw threaded brass screw.

40 placed the usual screw-threaded brass shell 20 and central plate 22 forming parts of the usual lamp socket. The torso is preferably formed of a plaster composition, and the shell 20 may be set in said socket 18 by plaster in the usual way. The base of the

45 plaster, in the usual way. The base of the torso 14 around the socket 18 preferably has a recess 24 therein for receiving the wires 26 which are attached to the shell 20 and plate 22 of the socket, so that the wires 26 lie flush with the outer surface of the socket. 30 50 designates the usual electric filament lamp, fitted in the socket 18.

40 designates the shade frame, formed of connected wires 42, 43, 44 and having the form of a hoop-skirt frame, the said frame 55 40 being adapted to be covered with light

fabric, such as silk, to form a skirt for the figure and to also act as a shade. This skirt or covering may be and preferably is, attached to the torso and draped over said frame 40.

The wire 44 is in the form of a partially closed ring, to which the upper ends of the vertical wires 42 are suitably connected, and another similar partially closed adjacent ring 46 is formed preferably from the same piece of wire, as by bending the said wire down and back upon itself, as indicated at 48. One end 49 of the ring 46 is preferably free, as indicated. A gap or space 50 is left between the ends of the rings 44, 46. 70

The base of the torso 14 is provided with a lug 60 which is preferably provided with a notch 62 therein. The base of the torso 14 is of slightly less diameter than the rings 44, 46 and is adapted to fit therein, the torso preferably having an encircling rib 64 adapted to rest on the said ring 44, and the gap 50 permits the lug 60 to move lengthwise thereof as the base of the torso 14 is fitted in the frame 40. When the torso and frame are together they may be fastened or locked together by turning the torso in the frame with the free end 49 of the ring 46 entering the notch 62 in said lug 60. The spring in said end 49 of the ring 46 will retard movement of said torso in said frame 40 tending to separate the two. The gap 50 also permits the wires 26 to pass into and out of said frame 40, facilitating the attachment and detachment of said bust 10 and frame 40. 75 80 85 90

The frame 40, preferably rests on a table or mantelpiece, and forms the support for the lamp.

What I claim is—

1. Means for connecting a wire frame to a base, having a partially closed ring providing a gap therein and a lug on the base adapted to pass into said gap and when turned interlock with said ring, said ring comprising a spring arm having a free end portion adapted to bear on said lug to retard turning of the parts. 95 100

2. Means for connecting a wire frame to a base, comprising a partially closed ring having a gap therein, and a lug on said base adapted to pass into said gap and when turned interlock with said ring, said base having a lamp socket in its lower part adapted to open into said frame, said ring comprising a wire having a free end, and 110 105

said lug having a notch into which said free end is adapted to enter when said base is turned in said frame.

3. Means for connecting a wire frame to a base, comprising a partially closed ring having a gap therein, and a lug on said base adapted to pass into said gap and when turned interlock with said ring, said base having a lamp socket in its lower part

adapted to open into said frame, said base having a slot in its outer side for containing electric wires, whereby said wires are flush with the exterior of said socket, for the purpose set forth.

In testimony whereof, I have signed my name to this specification this 25th day of April, 1924.

ALFRED MUNZER.
